UNITED STATES PATENT OFFICE.

CHARLES KOFSKE, OF APLINGTON, IOWA.

DESIGN FOR A RAILROAD-RAIL.

SPECIFICATION forming part of Design No. 33,474, dated October 30, 1900.

Application filed October 4, 1900. Serial No. 32,058. Term of patent 3½ years.

To all whom it may concern:

Be it known that I, CHARLES KOFSKE, a citizen of the United States, residing at Apling-ton, in the county of Butler and State of Iowa, have invented and produced a certain new and original Design for Railroad-Rails; and I do declare the following to be a full, clear, and exact description of the invention, such as will enable others skilled in the art to which it appertains to make and use the same.

The invention relates to a new and original design for railroad-rails; and it consists of a design of the shape and configuration shown in the accompanying drawings, in which—

Figure 1 is a perspective view of a railroad-rail, and Fig. 2 is an enlarged end view.

Referring to the drawings, 1 denotes the base of the rail, 2 the web, and 3 the tread, one corner of the latter of which is beveled, as shown at 4.

20

What I claim is—

The design for a railroad-rail as herein shown and described.

In testimony whereof I have hereunto set my hand in presence of two subscribing wit- 25 nesses.

CHAS. KOFSKE.
